Edward Brown Fitzgerald, Chicago, Ill., assignor to Dodge, Incorporated, Chicago, Ill., a corporation of Illinois

Application January 10, 1951, Serial No. 13,730

Term of patent 14 years

(Cl. D34—11)

To all whom it may concern:

Be it known that I, Edward Brown Fitzgerald, a citizen of the United States, residing in Chicago, Illinois, have invented a new, original and ornamental Design for a Combination Bank and Book End, of which the following is a specification, reference being had to the accompanying drawings, forming a part thereof, in which—

I claim:

The ornamental design for a combination bank and book end, as shown.

EDWARD BROWN FITZGERALD.
